UNITED STATES PATENT OFFICE.

WALTER F. STIMPSON, OF DETROIT, MICHIGAN.

DESIGN FOR A SCALE-BEAM.

SPECIFICATION forming part of Design No. 32,503, dated April 10, 1900.

Application filed February 9, 1900. Serial No. 4,699. Term of patent 14 years.

To all whom it may concern:

Be it known that I, WALTER F. STIMPSON, a citizen of the United States, residing at Detroit, in the county of Wayne and State of Michigan, have invented and produced a certain new and original Design for Scale-Beams, of which the following is a specification, reference being had therein to the accompanying drawings, in which—

Figure 1 is a front elevation of my scale-beam, and Fig. 2 is a perspective view thereof. A is a substantially-straight horizontal bar having at its opposite ends the uprights B and C. The upright C is provided with the outwardly and downwardly curved arm D. Centrally of the bar A is the downwardly-extending arm E, and to one side of this arm is the slightly-offset portion F, extending about half-way to the end of the bar and having at its opposite ends the rounded enlargements G.

The leading feature of my design is the substantially-straight horizontal bar, having a central depending arm and the slightly upwardly offset portion upon one side of said depending arm extending therefrom about ²⁵ half-way to the end of the bar, said offset portion having rounded enlargements at its opposite ends, the vertical uprights at the opposite ends of said bar and the curved arm extending outwardly and downwardly from one ³⁰ of said uprights.

What I claim as my invention is—

The design for a scale-beam, substantially as herein shown and described.

In testimony whereof I affix my signature ³⁵ in presence of two witnesses.

WALTER F. STIMPSON.
